FRANK FERRARA, OF MEDFORD, MASSACHUSETTS, ASSIGNOR TO SHAWMUT ENGINEERING COMPANY, OF DORCHESTER, MASSACHUSETTS, A CORPORATION OF MASSACHUSETTS

MECHANISM FOR AND METHOD OF PLACING YARNS ON CARRIERS FOR USE IN LOOMS

Application filed March 11, 1929. Serial No. 346,018.

My invention relates to arranging or preparing series of yarns and more particularly to the placement of tuft yarns upon a carrier or so-called tube frame for use in pile fabric looms, such as Axminster carpet looms. It aims to provide mechanism for placing the yarns, particularly where the yarn carrier or tube frame is provided with yarn tensioning or feedstop means, such for example as disclosed and claimed in my copending application, Serial No. 346,017, and includes also novel methods of arranging or positioning yarns for such use.

In the drawings illustrating by way of example means embodying my invention and whereby the method thereof may be practiced;

Fig. 1 is a view in vertical cross-section of so much of a yarn-placing or threading machine involving my invention as is necessary for a full understanding thereof;

Fig. 2 is a part view in front elevation of a portion of the mechanism of Fig. 1, those parts shown in Fig. 1 which would lie in front of the mechanism of Fig. 2 being omitted for the sake of clearness;

Fig. 3 is a vertical cross-sectional view corresponding to a portion of Fig. 1 but with certain clamping or holding means in normal or released position;

Figs. 4 and 5 respectively are a partial end view and bottom plan of the yarn carrier or tube frame, upon a larger scale; and

Fig. 6 is a view corresponding to Fig. 3 but illustrating a modification.

Referring now more particularly to the drawings, the yarn placing or threading mechanism as a whole and in its general arrangement may be of any usual or preferred construction, examples of such machine being shown for instance in the patents to Hathaway and Bixby Numbers 1,512,928 and 1,597,971, dated respectively October 28, 1924, and August 31, 1926. In the drawings of the present application sufficient of the mechanism is fully shown to afford a ready understanding of the invention. The machine includes a main frame 1 upon which are uprights, one of which is seen at 2, supporting a cross-piece or arch 3. A series or bank of

reciprocable needles 4 is mounted upon a head 5, suitable means such as one or more racks 6 moving in guides or bars 7 and meshing with a like number of pinions 8 being provided for actuating the needles. The latter are preferably directed in their movements as by means of a guide 9 related to the cross-head and needles in such manner that the latter and the guide may at times move together and at other times the needles may move relatively to the guide. If desired additional guide means 10 may be provided forwardly of that previously mentioned, it being supported between arms 11 projecting forwardly from the machine frame. Extending substantially from side to side of the machine frame is a support or seat 13 to receive and position a yarn carrier or tube frame 14 for the threading operation.

The yarn carrier or tube frame illustrated comprises the frame proper or bar 14 to which the barriers, spacers or guides 15 are secured as by means of an attaching strip 16 seen in Figs. 1 and 3 and upon a larger scale in Figs. 4 and 5. Said strip includes a flange 17 having formations for receiving one end of each of the series of guides 15, and a securing rib 18 of general U-shape in cross section. Across said rib are slots or the like 19 for receiving the respective guides, the latter being anchored as by means of a pin 20 inserted beneath said rib and passing through appropriate openings in the respective guides. The latter as illustrated are adapted for open or side threading. For retaining the yarns against lateral displacement and in proper spaced relation, each guide or barrier 15 has a laterally projecting nib 22 which provides, in conjunction with the next adjacent guide, a yarn passage 23 which may be further defined by a second or inner lateral projection or shoulder 24.

To retain the yarns against undesired withdrawal, retraction or running out, in a direction of their lengths, the yarn carrier or tube frame is provided with a feed-stop device or tensioner 25, the outer or free edge of which normally bears resiliently or yieldingly against the under edge of the respective nibs 22 of the series of guides. Said feed-stop 25

is formed of relatively thin metal of sufficient resiliency to permit it to be moved or sprung from its normal position, as in Fig. 3, downwardly into position as in Fig. 1 to permit the entrance of the needles 4 of the threading machine. It is secured to the main frame or bar 14 of the yarn carrier in any suitable manner as by welding or by being inserted beneath the back clips 26 and/or the end clips 27, Fig. 4, attached to said frame or bar.

The yarn carrier or tube frame per se as herein illustrated and described is fully disclosed and claimed in my copending application above mentioned.

Preparatory to the threading operation the carrier or frame is positioned upon its support or seat 13 on the machine. It is desirably then clamped in said position, with the guides or barriers 15 properly disposed to receive the bank or needles 4 through or between them. With a carrier or frame as shown in Figs. 1 to 5, however, the passages are blocked against entrance of the needles so long as the tensioner or feed-stop 25 remains in normal position. Accordingly I have provided means for opening the yarn passages in or between the several guides by displacement of said feed-stop or tensioning means 25.

Referring particularly to Figs. 1 to 3, a depressor or clamping member or bar 30 extends crosswise the machine, having at its lower portion a series of transverse openings or slots 31 with intermediate walls or teeth 32. Said openings 31 are spaced and arranged to come in alignment with the needles, while the intermediate walls or teeth 32 are in the planes of the bodies of the barriers or guides 15.

Said depressor is mounted for vertical movement into and out of position to open the yarn tensioner or feed-stop 25 and, if desired, also to clamp the frame 14 in position upon its seat 13. Accordingly it is provided with upwardly projecting ears 33 receiving pins 34 at the lower ends of vertical arms 35. The arch 3 has secured to it a corresponding number of similarly spaced bearings 36 provided with an eccentric and preferably adjustable bushing 37 supporting a shaft 38. Upon said shaft are pinned eccentrics 39, one for each of the vertical arms 35 previously mentioned, the latter having straps 40 at their upper ends received on the respective eccentrics. One or more hand levers 41 are provided upon the shaft 38 for rocking it thereby to raise or lower the depressor or clamp bar 30. Prior to operation of the machine said depressor is moved downwardly until the lower faces of its walls or teeth 32 contact with the feed-stop or tensioner 25, depressing the latter sufficiently to open the yarn passages of the guides 15 for entrance of the needles. If it is to serve also as a

clamp for the frame or carrier as a whole, as illustrated, it is forced sufficiently downwardly firmly to clamp and hold the latter in position for threading. The several vertical arms 35 and associated parts are distributed along the depressor or clamping bar 30 in such manner that the pressure is applied equally through the entire length of the latter.

From the foregoing it will be understood that the feed-stop or yarn tensioning means 25 of the yarn carrier is simultaneously controlled or opened with respect to the entire series of guides 15 and this without interference with the operation of the needles, by reason of the provision of the openings or slots 31 aligned with the passages in or between the guides. In addition the walls or teeth 32 of the depressor serve as guides for the needles as they advance to engage the yarns Y and as they retreat with said yarns.

The depressor element 30 as illustrated is also provided with a member adapted to engage the upper edges of the series of guides 15. Said member includes a horizontal portion 43 overlying the guides and depending or vertical portion 44 of a total vertical extent not exceeding the distance from the top of each of the guides down to the yarn passage 23, that is, down to the bottom of the deflected nib 22. Said means 43, 44 is preferably supported upon the depressor 30 in a manner permitting it to yield upwardly with respect to the latter. Accordingly it has secured to it a plurality of pins or bolts 45 extending upwardly through corresponding openings in the overlying portion of the depressor. Coil springs 46 surround each of said bolts, bearing at the lower ends against the horizontal part 43 of the yieldable means 105 and at their upper ends against the bottoms of bores 47 in the depressor. Said springs thus normally urge the yieldable means 43, 44, downwardly into the position such as illustrated in Fig. 3, that is, during the raised or inoperative position of the depressor. As the latter is brought down by means of the hand levers 41 said yieldable means 43 comes into contact with the upper edges of the guides 15. Its further downward movement 115 is thus prevented, but the depressor proper is permitted to continue downwardly into depressing engagement with the tensioner 25 and, when so desired, into clamping relation with the frame as a whole, through said tensioner.

The position of the described parts is then substantially as in Fig. 1. It will be noted that the vertical portion 44 of the yieldable means is not of sufficient length to extend 125 down into the path of the needles 4. Said yieldable means 43, 44 additionally clamps and aligns the frame, through its engagement with the guides 15. It also serves to bring any of the guides which may acciden- 130

tally have been deflected, back into proper relation with the others of the series, but due to its yieldable connection with the depressor 30 it cannot engage the guides so forcibly as 5 to tend to bend or spring them out of proper alignment or to disengage them from the carrier bar.

It will be understood that the ends of the series of yarns Y to be placed or threaded in 10 the yarn carrier or tube frame are supported for engagement by the needles, substantially as shown in Fig. 1. The extremities of the several yarn ends or units are held in a so-called yarn-end clamp or holder 50, one for 15 each spool of yarns, removably seated in a clamp holder 51 mounted on the arms 11 of the machine frame previously mentioned. During the threading operation the spool or spools carrying the yarns are supported 20 in any suitable manner, for example, as in the Hathaway and Bixby patents previously mentioned.

In Fig. 6 is illustrated a yarn carrier or frame having a modified form of means for 25 practicing the method of my invention. The frame proper 14 is shown upon its support or seat 13 on a threading machine, as in Figs. 1 to 3, in position to be threaded by the needles 4. In this instance the yarn tensioning or 30 feed-stop means comprises one or more spring strips 55 secured to the frame as by the clips 26. At its free portion, underlying the nibs 22 of the guides 15, said strip element 55 is formed with a deflected or cam 35 portion 56 which is adapted to be engaged by the needles themselves and to be sprung downwardly thereby to give them free passage. In some instances it is thus possible to dispense with depressing means on the 40 threading machine for opening said tensioning or feed-stop device, or, if desired, such means as in Figs. 1 to 3 may be employed in conjunction with the frame with a needle-operable tension stop as in Fig. 6, thus insuring 45 that any needle which might be out of line with the others would not be interrupted by the tension strip as it might otherwise be if the latter were insufficiently depressed.

From the foregoing it will be apparent 50 that my invention includes that method of threading or positioning a series of yarns in a yarn carrier or tube frame of the character described, by the following steps or some of them: supporting or clamping the carrier 55 or frame in proper alignment with a series of needles, opening passages in or between spacing members or guides of the yarn frame to permit the entrance of the needles, advancing the needles into engagement with 60 the yarns and retracting them carrying the yarns with them, and closing the yarn passages and holding the yarns therein against longitudinal movement either immediately or automatically upon removal of the carrier or frame from the threading machine.

Having thus described one illustrative embodiment of my invention and a manner of practicing the methods thereof it will be understood that the invention is not limited to the particular constructions or to the exemplary methods herein shown and described, its scope being pointed out in the following 70 claims.

I claim:

1. In a machine for threading tuft-yarn carriers equipped with yarn guides and with yarn-tensioning means projecting at least partly across the yarn passages of said guides, a bank of reciprocable needles, a support whereon the carrier is positionable with its yarn passages respectively in line with said needles, an elongated element parallel with said carrier support, and means to move said element toward and away from the path of the needles, said element having a leading portion constructed to permit passage of the needles transversely thereof and adapted to engage said tensioning means of the carrier to clear the needle path.

2. In a machine for threading tuft-yarn carriers equipped with guides providing yarn passages and with cooperating yarn-tensioning means normally at least partly blocking said passages, a support on the machine for such carrier, a movable bar-like element along and spaced from said support, and means to move said element to bring it into opening engagement with said tensioning means of a supported carrier.

3. In a machine for threading tuft-yarn carriers equipped with yarn guides and with yarn-tensioning means projecting at least partly across the yarn passages of said guides, a bank of reciprocable needles, a horizontal seat for a carrier to position the same for threading by said needles, a vertically movable bar parallel with and above said carrier seat, the lower edge of said bar formed with a series of alternate transverse openings and walls, and means to move said bar into and out of a position wherein said walls engage and depress said tensioning means out of the paths of the needles while said openings are brought into line with the needles.

4. In a machine for threading tuft-yarn carriers equipped with yarn guides and with yarn-tensioning means projecting at least partly across the yarn passages of said guides, a bank of reciprocable needles, a horizontal seat for a carrier to position the same for threading by said needles, a vertically movable bar parallel with and above said carrier seat, the lower edge of said bar formed with a series of alternate transverse openings and walls, means to move said bar into and out of position wherein said walls engage and depress said tensioning means out of the paths of the needles while said openings are brought into line with the needles.

- needles, and means on said bar yieldingly engageable over the yarn guides of the carrier in the depressing position of said bar.
5. In a machine for threading tuft-yarn carriers equipped with guides providing yarn passages and with cooperating yarn-tensioning means normally at least partly blocking said passages, a support on the machine for such carrier, a movable bar-like element along and spaced from said support, means to move said element to bring it into opening engagement with said tensioning means of a supported carrier and simultaneously to clamp said carrier as a whole upon said support.
- 10 6. In a machine for threading tuft-yarn carriers equipped with guides providing yarn passages and with cooperating yarn-tensioning means normally at least partly blocking said passages, in combination, a bank of reciprocable needles, a support for positioning the carrier with the yarn passages thereof in alignment with said needles, and means movable toward and away from said support to engage and depress the yarn-tensioning means of the positioned carrier thereby to open the yarn passages for projection and retraction of the needles there-through, said means having along its engaging portion a series of formations through which the needles may be passed.
- 20 7. In a machine for threading tuft-yarn carriers equipped with guides providing yarn passages and with cooperating yarn-tensioning means normally at least partly blocking said passages, in combination, a bank of reciprocable needles, a support for positioning the carrier with the yarn passages thereof in alignment with said needles, a bar extending along and movable toward and away from said support to clamp the carrier thereon, and means on said bar to depress or open the yarn-tensioning means of the carrier.
- 25 8. In a machine for threading tuft-yarn carriers equipped with guides providing yarn passages and with cooperating yarn-tensioning means normally at least partly blocking said passages, in combination, a bank of reciprocable needles, a support for positioning the carrier with the yarn passages thereof in alignment with said needles, and a longitudinal element movable toward and away from the said support and having along its leading portion means for engaging and opening or depressing the yarn-tensioning means of the positioned carrier but leaving the paths of the needles unobstructed.
- 30 9. In a machine for threading tuft-yarn carriers equipped with guides providing yarn passages and with cooperating yarn-tensioning means normally at least partly blocking said passages, a support on the machine operatively to position such carrier for threading, and means movably supported on
- the machine simultaneously to open all said passages for threading.
10. That method of placing and holding a series of tuft yarns or yarn units for use in a loom which comprises, providing a spool-supporting yarn carrier with passages for spacing and guiding the individual yarns or yarn units, at least partially and yieldably blocking said passages against free movement of the respective yarns or units there-through, passing yarn-engaging needles through said passages and thereby clearing the latter, withdrawing said needles and the yarns engaged by them and to place the latter in the respective passages, and again yieldably blocking said passages sufficiently to prevent undesired longitudinal movement of the yarns so placed therein.
- 70 11. That method of placing and holding a series of tuft yarns or yarn units for use in a loom which comprises, providing a spool-supporting yarn carrier with passages for spacing and guiding the individual yarn or yarn units, yieldably and commonly uniformly constricting or barring said passages, rigidly supporting the carrier for drawing of the yarns into its passages, mechanically deflecting simultaneously, commonly and uniformly the constricting or barring means for all passages, drawing in the yarns or yarn units simultaneously through the respective passages, and thereafter again simultaneously and commonly yieldably constricting the latter uniformly sufficiently to retain the yarns again undesired withdrawal, 100 retraction or advancement with respect to said passages, during transportation or use of the carrier.
- 80 12. In testimony whereof, I have signed my name to this specification.
